UNITED STATES PATENT OFFICE.

EDWARD B. HESS, OF NEW YORK, AND JOSEPH M. STOUGHTON, OF YONKERS, NEW YORK, ASSIGNORS TO THE CENTURY MACHINE COMPANY, OF NEW YORK, N. Y.

TYPE-WRITING MACHINE.

SPECIFICATION forming part of Letters Patent No. 620,774, dated March 7, 1899.

Application filed August 19, 1898. Serial No. 688,981. (No model.)

To all whom it may concern:

Be it known that we, EDWARD B. HESS, of the city and county of New York, and JOSEPH M. STOUGHTON, of the city of Yonkers and county of Westchester, State of New York, citizens of the United States of America, have invented certain new and useful Improvements in Type-Writing Machines, of which the following is a specification.

10 This invention relates to that class of type-writing machines in which pivoted type-bars are each provided with a plurality of type or characters arranged longitudinally thereon and each bar operated upon through the medium of a plurality of finger-keys, one for each character, and one or more of which impart to the type-bar a motion around its pivot and longitudinally or in the direction of its length to bring the desired character to the point of printing or impact upon the platen. Machines of this general class are shown in the patents to Burridge, Nos. 585,838, 593,563, and 594,777. A machine more intimately allied in details of construction to that herein described is also shown in a patent to us, No. 610,400, dated September 6, 1898, and upon which the invention of the present specification is in its main features more particularly an improvement.

30 In the machine herein described, as in that of the above application, each type-bar is equipped with a sleeve having three type-carrying faces, upon each of which a series of type is arranged longitudinally, three type being shown upon each such face. Each type-carrying sleeve may be partially rotated at will to bring the type or characters upon either of its three surfaces opposite the platen in proper position to print when the lever is operated. Three keys are shown for each lever, and each key when depressed brings to the printing-point the corresponding character upon that face of the type-carrying sleeve then opposite the platen.

45 The invention consists, primarily, in two features—first, the organization by which a type-lever is actuated to bring either of three characters then opposite the platen to the printing-point upon the platen, and, second, the organization relating to the partial rota-

tion of the sleeve or part of the type-bar having thereon the type or characters to be printed.

The organization by which the three keys of each type-lever effect the three phases of movement of that lever is not dependent upon the organization relating to the partial rotation of the type-carrying sleeves or parts, nor is the latter organization dependent upon the former. The key mechanism may be used with a different organization for bringing different series of type or characters opposite the platen, and the latter mechanism may be employed in machines having a different key mechanism from that herein shown. 60 65

In the accompanying drawings, Figure 1 is a vertical section at right angles to the cylindrical platen; Fig. 2, a similar section looking in the opposite direction and showing the key mechanism for operating one of the type-bars; Fig. 3, a similar section taken at the side of the machine, showing the shifting-keys and mechanism for effecting a partial rotation of the type-carrying sleeves; and Fig. 4, a view of the same mechanism at right angles to Fig. 3. Figs. 5 and 6 are respectively detail views of pivoted slotted plates operated by the shifting-keys to accomplish the partial rotation of the type-carrying parts or sleeves; Fig. 7, a plan view of a part of the machine, showing the type-carrying sleeves and a means for effecting their partial rotation. Fig. 8 is a rear view of the same parts, showing also the device for guiding the type-bars to bring their type-carrying sleeves into gear with the shifting-rack and the locking-comb for holding the type-bars while the type-carrying sleeves are being shifted or partially rotated. Fig. 9 is a bottom view showing more particularly the latter device. Figs. 10, 11, and 12 are detail views showing the type-carrying sleeves and locking-latches to secure them in either position to which they may be shifted or partially rotated. Figs. 13, 14, 15, and 16 are detail views showing modifications of the locking-latches of the sleeves; Fig. 17, a section with some of the parts removed on the line 17 17 of Fig. 1. 80 85 90 95

For each type-bar there is a vertical plate 100

1, pivoted at its lower end in the bed-plate and having in its enlarged or widened upper end three slots 2 3 4. The upper and substantially horizontal slot 2 is preferably 5 curved concentric to the pivot of the plate and connects at its ends with the downwardly-extending slots 3 4, which first diverge, inclining, respectively, toward the front and rear of the machine, and then near 10 their bottoms converge at a comparatively slight angle. The length of the slots and their shape, arrangement, and location are such as to effect the operations hereinafter described. For each such plate there are 15 three finger-keys 5 6 7, and the keys 5 7 carry laterally-projecting lugs or studs 5' 7', which when the keys and other parts are in their normal inactive positions, as shown in Figs. 1 and 2, occupy the ends of the slot 2. 20 The lugs 5' 7' act as stops to limit the rise of the keys 5 7 and also when both these keys are inactive as stops to prevent motion of the plate 1 about its pivot. The central key 6 may have a cross-pin 6' engaging the under 25 face of the top plate to limit its upward movement. The keys may be constructed in any desired manner. As shown, each has at its lower end a lateral projection with an aperture through which passes a vertical pin 8, 30 fixed in the bed-plate, a coiled spring 9, surrounding the pin, being interposed between the lateral projection of the key and the bed-plate.

Each type-bar 10 may be constructed in 35 any suitable manner of one or more pieces and is pivoted at 10' in the rear end of a horizontal bar or plate 11, pivoted at 11' on the plate 1 and pivotally connected at its front end to a vertical bar 12, rocking upon a pivot 40 12' in the bed-plate. At a suitable point between the pivots 11' 12' a horizontal bar 13 is pivoted to the bar 12, and at or near its rear end the bar 13 is connected by a swiveling link 14 with a projection on the type-bar adjacent to its pivot. The rear end of bar 13 is guided in a vertical slotted guide-plate 15, and the front end of the bar 11 has an upwardly-extending projection similarly guided in a slot in a horizontal plate 15'. Preferably 45 the horizontal bar 11 is formed with a hook 16 at its upper edge, the vertical part of which extends across the slot 2 and the horizontal part above the lug or stud 5'. The upper edge of the hook works in a slot in a 50 transverse slotted rod 17. In these or any other suitable ways the mechanism may be guided and braced against lateral strains. Each key near its lower end has a foot or projection 18, extending above a pin or stud 19, 55 projecting laterally from the bar 13, and the bar 13 extends over the transverse bar 20, which is the universal bar of the machine, and controls the carriage and ribbon feed, as hereinafter described.

60 65 As is well understood, each type-bar 10, except the middle one, is angularly displaced or bent with reference to a horizontal plane to

bring the letters or characters thereon to the proper printing-point on the platen. Also the axis of the pivot 10' of each type-bar is at 70 such angle to the axis of the platen-roller as to cause the characters on the type-bars to properly converge on the printing-point when the bars are actuated to take an impression. This may be conveniently accomplished by 75 deflecting the rear ends (those nearest the platen) of the bars 11 on each side of the central one to which the central type-bar is pivoted. This is well understood and is shown in Figs. 1 and 17. On the depression of the 80 center key 6 its foot 18, acting upon the pin 19, carries down the bar 13 and the type-bar 10 is thrown to bring the middle type or character *b* to the printing-point on the platen. The parts are returned to normal position by 85 the springs 9 and 13', and no special device is required during the movement of the key to hold the plate 1 stationary, the lugs 5' 7' performing this function. If the key 7 be depressed, the same operation occurs, with the 90 addition that a longitudinal movement of the type-bar toward the rear of the machine occurs, so that the letter or character marked *c* is brought to the printing-point. This operation is effected by the lug 7' passing down 95 the inclined slot 4 in the plate 1, thus rocking the plate 1 upon its pivot and carrying it toward the rear of the machine until the lug enters the reversely-inclined bottom part of the slot, which, however, now stands vertically with the plate in the angular position into which it has been rocked. The movement of the plate therefore ceases, and the continued descent of the key produces the impact of the type upon the platen. During 100 this operation the slot 2 permits the free movement of the plate 1 relatively to the lug 5' on the key 5. When the key 5 is depressed, precisely the same operation occurs, except that the lug 5' now moves the plate 1 toward the 105 front of the machine, thus imparting a longitudinal movement to the type-bar in the reverse direction, thus bringing the character which is arbitrarily marked *a* to the printing-point on the platen. This organization possesses several advantages, among which may be mentioned the positive holding of the plate 1 in its normal position and when the center key is depressed by the devices which cause 110 its operation when the other two keys are depressed, thus giving rigidity and stability to the parts without the employment of any special mechanism for that purpose.

The mechanism relating to the partial rotation of the type-sleeves or parts of the type-bars will now be described.

Each type-bar carries at its outer end a rotatable sleeve 21, mounted thereon in any suitable manner and having three faces marked A B C, each of which carries three characters, longitudinally arranged and arbitrarily marked *a b c*. The back of each sleeve is formed with gear-teeth 22, adapted to mesh when the type-bars are in the normal elevated

position with the teeth of an endwise-movable rack 23. A pivoted latch 24 is adapted to engage with either of three notches in a plate 25, secured to the end of the sleeve, and has a prolonged end 26, on which bears a spring 27, that tends normally to throw the latch into engagement with the notched plate 25. The rack 23 is curved and is mounted, through the medium of slots and set-screws 28 or in any suitable manner, upon a bracket or part 29 of the frame, also preferably curved. Below the rack is mounted a slotted type-bar-guiding plate 30. This plate is preferably curved reversely to the rack 23 and has a series of 15 slots, one for each type-bar, which are flared or widened at their outer ends and closely fit the type-bars at their inner ends, so that as a type-bar rises it is sure to enter its slot and be accurately guided to bring the gear-teeth 20 thereon into operative engagement with the teeth upon the rack 23. The guide-plate 30 is fixed at 31 upon the bracket or part 29 of the frame.

It will be obvious that if the center type-bearing faces A of the type-bearing sleeves are opposite or facing the platen they may all be partially rotated in either direction (provision being made for operating the latches if employed) by the movement of the rack, so as to bring either the type-bearing faces B or C opposite the platen. Either type-bearing face of any type-bar being thus brought opposite the platen either character thereon arbitrarily marked *a b c* may be brought to 35 the printing-point at will by the manipulation of the keys 5, 6 or 7. This general operation is disclosed in our application above referred to, and the present invention relates to improved means for operating the rack, 40 means for locking the type-bars while the sleeves are being partially rotated, and means for releasing the sleeves to permit of their partial rotation and locking them in either of their three positions. The locking of the 45 type-bars may be accomplished in a variety of ways without departing from the principles of this invention. The specific form in which this part of the invention is embodied consists in a locking-comb 33, having curved 50 or hooked teeth 34, forming recesses, one for each type-bar. This comb is curved to correspond to and is mounted upon the slotted type-bar-guiding plate 30, so as to move endwise thereon in any suitable manner, slots 55 and set-screws 35 being shown. Normally the free way or unobstructed openings formed by the curved teeth of the locking-comb coincide with the slots in the type-bar-guiding plate, so that the type-bars are free to rise 60 to their highest position until they come to the bottom of the slots in the guide-plate. When the sleeve-shifting rack 23 is to be operated, as hereinafter described, the locking-comb is caused to move endwise in the direction of the arrow, so that its curved teeth will embrace and firmly hold the type-bars. The shifting-rack 23 is then operated to bring

either face B or C of the type-bearing sleeves opposite the platen, and then the locking-comb recedes to release the type-bars and permit 70 their operation through the medium of the finger-keys, as already described. The type-bearing sleeves may be frictionally or otherwise mounted upon the type-bars, so as to yield to the stress of the shifting-rack and 75 remain in any position into which they may be removed thereby. It is preferred, however, to positively lock the sleeves, and this is accomplished by providing upon the locking-comb 33 a series of upright pins or studs 80 36, each of which engages the tail or extension 26 of a locking-latch 24, when the locking-comb is moved in the direction of the arrow to lock the type-bars. By this operation the latches are lifted out of engagement 85 with the notches on the type-bearing sleeves, their partial rotation by the shifting-rack being permitted, and on the retrogression or reverse movement of the locking-comb the latches again engage notches on the type-bearing 90 sleeves and lock them positively in their new position. This is clearly shown in Fig. 1, the pins 36 and latches 24 being omitted in other general views for the sake of clearness of illustration.

The means by which the shifting-rack and locking-comb are operated will now be described.

Two shifting-keys 37 38, Figs. 3 and 4, mounted and equipped with returning-springs 100 similarly to the finger-keys 5 6 7 and preferably located at the left of the keyboard, have, respectively, laterally-projecting pins or lugs 37' 38', each working in the slots of two vertical adjacent parallel plates 39 40, rocking 105 on pivots in or on the bed-plate. The plate 39 has a horizontal slot 39', opening at its ends into downwardly-extending slots 39² 39³, diverging throughout the greater part of their length at a suitable angle from a vertical line 110 passing through the pivot of the plate when in the normal position and at their lower ends converging slightly. The plate 40 has also three slots, a horizontal one, 40', somewhat longer than the slot 39', opening at its 115 ends into downwardly-extending slots 40² 40³. The slots 40² 40³ first incline abruptly in the same direction, (to the right, as viewed in Figs. 4, 5, and 6,) and are then throughout the greater part of their length both slightly 120 inclined in a reverse direction, this inclination being abruptly increased near the bottom of the slots. The keys are shown as arranged on opposite sides of the pair of plates, and their pins 37' 38' project through the 125 horizontal slots of both plates and normally occupy the ends of the slot 39'. The upper end of the plate 39 is connected by a pivoted link 41 with one end of a lever 42, fulcrumed at 43 on a brace-bar 44', connecting the brackets 29 and slotted guide-plate 30. The upper end of the lever passes through a slot in the bracket 29 and is operatively connected 130 with the endwise-movable rack 23. The up-

per end of the plate 40 is pivotally connected to a bar 44, sliding with sufficient freedom of movement by means of a slot and screw 45 on one of the side bars 46 of the frame and having a laterally-projecting pin 47 extending between the bifurcation of a lug 48 on the locking-comb 33, projecting through a slot in the guide-plate 30, Figs. 4 and 9. If the shifting-key 37 be depressed, the pin 37' first 10 rides against the abruptly-inclined side of the upper part of slot 40², and the bar 44 is drawn to the left, moving the locking-comb in the direction of the arrow, causing its curved or hooked teeth to embrace the type-bars and its lugs 36 to lift the latches 24 out of engagement with the type-carrying sleeves. In its further descent the pin 37' does not 15 produce any further movement of the plate 40, because the central part of the slot 40² is now vertical, but it acts upon the inner edge of the inclined slot 39² and rocks the plate 39 to the right, thus causing the rack 23 to move endwise and partially rotate the type-sleeves to bring one of its side type-bearing surfaces 20 opposite the platen. In the further movement of the pin 37' it runs in the now vertical lower part of the slot 39², the plate 39 remaining therefore stationary, and in the abruptly-inclined lower part of slot 40², therefore 25 by producing a reverse or retrograde movement of the locking-comb, which releases the type-bars and permits their latches to again engage the type-carrying sleeves and lock them in their new position. The type-bars 30 may now, while the shifting-key 37 is held down, be operated, as already described, by the finger-keys 5 6 7. When the key 37 is released, the parts return to normal position. On the depression of the shifting-key 40 38 the same operation of the locking-comb occurs, but the rack now moves in an opposite direction, thus bringing opposite the platen the third or remaining type-bearing faces of the sleeves. A spring 49, Fig. 9, may 45 be applied to the bar 44, that operates the locking-comb and tends to return the locking-comb to its normal position. On each type-bar adjacent to the type-bearing sleeve is a centering or truing pin 50, which enters either 50 one of three guide-sockets in a block 51, arranged adjacent to the platen 52, Figs. 1 and 10.

Figs. 15 and 16 show a slight modification of the latch for locking the type-bearing sleeve. The latch 24 is straight and rocks in a single plane parallel with the axis of the sleeve and is operated on by the inclined face 36' of a stud carried by the locking-plate 33. Figs. 13 and 14 show another modification. 55 Here the plate 25 at the end of the sleeve is provided with three apertures 25', whose axes are parallel with the axis of the sleeve. A locking-pin 25², sliding endwise in a bearing on the type-bar, has an angular end 25³ working in an inclined slot in a lever 25⁴. A lug or projection on the locking-comb 33 operates the lever to withdraw the pin from one of the

apertures, while a coil-spring returns the lever and locking-pin to the normal position when the locking-comb 33 recedes. The 70 screw that forms the pivot of the lever may also, as shown, be the centering or truing pin 50.

The platen or cylinder 52 is mounted in standards near the ends of the carriage 53. 75 The carriage may slide in seats or ways in two lines of posts 54, mounted on the bed-plate and be held thereon by strips or plates 55. Any suitable arrangement or style of platen and platen-carriage and means for actuating them may be adopted. Posts projecting from the bottom of the carriage carry the ratchet-plate 56. Any suitable arrangement of spring or weight tends to propel the carriage from right to left of the machine, as 80 usual, none being shown in the drawings.

57 is the feed latch or pawl device engaging the ratchet-plate. As shown in Fig. 1, the latch rocks on trunnions 57', having bearings in adjacent posts 54 of the inner row or 90 series of such posts, and at its front end 57² is pivotally connected to a short link 58, pivoted to a bar 58', that connects the rear ends of the side bars 59 of the universal bar 20. At a suitable point between their ends these 95 side bars are connected by a rock-shaft 60, having bearings in posts 61, located at or near the sides of the machine. Springs 62 (shown as coiled around the rock-shaft and having their free ends bearing, respectively, against 100 the posts 61 and side bars 59) tend to hold the universal bar 20 against the bars 13 of the type-bar-actuating devices and throw down the rear ends of the side bars.

In Fig. 1 we have merely indicated at X a 105 rocking ribbon-carrier. Any suitable ribbon-carrier and ribbon-feed mechanism may be employed, and the invention is in no way dependent upon or particularly related to the ribbon mechanism indicated. 110

The form in which the accompanying drawings show our invention embodied has now been described in detail. It is plain, however, that variations thereof may be made in its different parts without departing from the 115 invention or principles of construction and operation. No attempt will be made to point out modifications in the construction described, except that it is deemed expedient to refer to the movable plate 1. Of course with 120 some special means for limiting the rise of the keys 5 and 7—such, for instance, as is shown in connection with 6—the upper wall of the slot 2 may be removed, the primary purpose of the special arrangement of the 125 slots being that the lugs 5' and 7' shall act as stops for the plate and that between the lugs there shall be a slot, passage, or free way for the accommodation of the inactive lug during the movement of the plate. It is also 130 plain that the slots 3 and 4 might be diverged throughout their length or not convergent at their lower parts, they being then of such length and the pins 5' 7' so related to them

that on the complete depression of the key the pivot of the type-bar will be brought to the proper position and the type just out of contact with the platen. The usual quick impulse given to the key would impart such motion to the type-bar that the momentum of the end of the bar to which it would naturally yield would be sufficient to bring the type against the platen with a sharp impact.

10 We claim as our invention—

1. The combination of a platen, a type-bar having two type placed longitudinally thereon, the pivot of the type-bar, a plate movable toward and from the platen and correspondingly determining the position of the type-bar pivot relatively to the platen and having therein a horizontal slot opening at its ends into two diverging slots, two keys having lugs that normally occupy the ends of the horizontal slot and travel in the diverging slots when the keys are depressed, whereby the plate is moved away from the platen when one key is operated and toward the platen when the other is operated, and means for swinging the type-bar about its pivot when either key is depressed.

2. The combination of a platen, a type-bar having two type arranged longitudinally thereon, a movable support to which the bar is pivoted, a rocking plate to which such support is connected having three slots therein, a horizontal slot connecting at its ends with two divergent slots, two keys having lugs or projections normally occupying the ends of the horizontal slot and traveling in the divergent slots when depressed to rock the plate either toward or away from the platen, and correspondingly move the type-bar support either forward or back, and means operated by the depression of either key to swing the type-bar on its pivot.

3. The combination of a platen, a type-bar having three type arranged longitudinally thereon, a movable support to which the bar is pivoted, a rocking plate to which said support is connected having three slots therein, a horizontal slot connecting at its ends with two divergent slots, three keys, two of which have lugs or projections normally occupying the ends of the horizontal slot and traveling in the divergent slots when depressed to rock the plate toward or away from the platen, and correspondingly move the type-bar support either forward or back, the third key when depressed not acting upon the rocking plate, and means for swinging the type-bar upon its pivot when either of the three keys is depressed.

4. The combination of a platen, a type-bar having two type placed longitudinally thereon, the pivot of the type-bar, a plate rocking on a pivot toward and away from the platen and correspondingly determining the position of the type-bar pivot relatively to the platen and having therein a horizontal slot opening at its ends into two diverging slots, two keys

having lugs that normally occupy the ends of the horizontal slot and travel in the diverging slots when the keys are depressed, whereby the plate is moved away from the platen when one key is depressed and toward the platen when the other is depressed, and means for swinging the type-bar about its pivot when either key is depressed.

5. The combination of a platen, a type-bar having two type placed longitudinally thereon, the pivot of the type-bar, a plate rocking on a pivot toward and away from the platen and correspondingly determining the position of the type-bar pivot relatively to the platen and having therein a horizontal slot opening at its ends into two diverging slots, which near their lower ends are slightly convergent, two keys having lugs that normally occupy the ends of the horizontal slot and travel in the other slots, when the keys are depressed, whereby when either key is depressed the plate is first moved either toward or away from the platen and remains at rest during the remainder of the downward excursion of the key, and means for swinging the type-bar about its pivot when either key is depressed.

6. The combination of the vertical rocking plate having a horizontal slot opening at its ends into two diverging slots, keys having lugs normally occupying the ends of the horizontal slot and that travel in the divergent slots when the keys are depressed, a horizontal bar 11 pivoted on the rocking plate, a type-bar pivoted on the rear end of said bar 11, a vertical bar pivotally connected with the front end of bar 11 and rocking on a pivot at or near its lower end, a second horizontal bar 13 pivoted to the vertical bar at its front end, a link connection between the rear end of said horizontal bar and the type-bar, means whereby when either key is operated the second horizontal bar is depressed, slotted guide-plates 15, 15', and the universal bar 20, substantially as and for the purpose set forth.

7. The combination of a series of type-bars having rotatable type-bearing sleeves with multiple type-bearing faces, mechanism for partially rotating the sleeves to bring the desired type-bearing faces thereof into position for printing, and devices for locking or holding the type-bars in engagement with said mechanism during the operation of partially rotating the sleeves.

8. The combination of a series of type-bars having rotatable type-bearing sleeves with multiple type-bearing faces, shifting mechanism for partially rotating the sleeves to bring the desired type-bearing faces into position, devices for locking the type-bars and holding the sleeves in engagement with said mechanism during the operation of partially rotating the sleeves, a type-sleeve-shifting key and interposed mechanism connecting it with the shifting mechanism and locking devices, whereby on the depression of said key the type-bars are first locked, the shifting

mechanism then actuated to partially rotate the sleeves, and finally the locking devices thrown out of engagement with the type-bars.

9. The combination of a series of type-bars having rotatable type-bearing sleeves with multiple type-bearing faces, shifting mechanism for partially rotating the sleeves to bring the desired type-bearing faces into position, devices for locking the type-bars and holding the sleeves in engagement with said mechanism during the operation of partially rotating the sleeves, a type-sleeve-shifting key and interposed mechanism connecting it with the shifting mechanism and locking devices, whereby on the depression of said key the type-bars are first locked, the shifting mechanism then actuated to partially rotate the sleeves, and finally the locking devices thrown out of engagement with the type-bars, and a finger-key for operating each type-bar when either type-bearing face of the sleeve is in proper position.

10. The combination of a platen, type-bars having rotatable type-bearing sleeves, each with multiple type-bearing faces and two type longitudinally arranged on each such face, two keys and operative connections between the keys and type-bars whereby either type on any face of the sleeve then opposite the platen may be brought to the printing-point by the manipulation of the corresponding key, mechanism for partially rotating the sleeves to bring their desired type-bearing surfaces opposite the platen, and devices for locking the type-bars and holding the sleeves in engagement with said mechanism during the operation of partially rotating the sleeves.

11. The combination of a platen, type-bars having rotatable type-bearing sleeves each with multiple type-bearing faces and three type longitudinally arranged on each such face, three keys and operative connections between the keys and type-bars whereby either type on any face of the sleeve then opposite the platen may be brought to the printing-point by the manipulation of the corresponding key, mechanism for partially rotating the sleeves to bring their desired type-bearing surfaces opposite the platen, and devices for locking the type-bars and holding the sleeves in engagement with said mechanism during the operation of partially rotating the sleeves.

12. The combination of type-bars having rotatable type-bearing sleeves, each with multiple type-bearing faces, mechanism for partially rotating the sleeves to bring the desired type-faces thereof into the desired position, devices for locking the type-bars and holding the sleeves in operating engagement with the mechanism for partially rotating them, means for first throwing the locking devices into operation, means for then operating the sleeve-rotating mechanism, and means for then throwing the locking devices out of operation.

13. The combination of type-bars having rotatable type-bearing sleeves, each with multiple type-bearing faces, a locking-latch for

each sleeve to hold it positively in any position to which it may be adjusted, mechanism for partially rotating the sleeves to bring the desired type-faces thereof into the desired position, and means for disengaging the latches from the sleeves before said mechanism has operated and causing the reengagement of the latches with the sleeves after said mechanism has operated.

14. The combination of type-bars having rotatable type-bearing sleeves, each with multiple type-bearing faces, a locking-latch for each sleeve to hold it positively in any position to which it may be adjusted, mechanism for partially rotating the sleeves to bring the desired faces thereof into the desired position, devices for locking the type-bars and holding the sleeves in operative engagement with the mechanism for partially rotating them, devices for disengaging the latches from the sleeves while the type-bars are locked, means for first operating the type-bar-locking devices and latch-disengaging devices, then the type-sleeve-rotating mechanism and finally throwing the type-bar-locking devices and latch-disengaging devices out of operation.

15. The combination of type-bars having rotatable type-bearing sleeves each with multiple type-bearing faces, a locking-latch for each sleeve to hold it positively in any position to which it may be adjusted, mechanism for partially rotating the sleeves to bring the desired faces thereof into the desired position, devices for locking the type-bars and holding the sleeves in operative engagement with the mechanism for partially rotating them, devices for disengaging the latches from the sleeves while the type-bars are locked, means for first operating the type-bar-locking devices and latch-disengaging devices, then the type-sleeve-rotating mechanism and finally throwing the type-bar-locking devices and latch-disengaging devices out of operation, and keys for operating the type-bars when either of their faces is in printing position.

16. The combination of a platen, type-bars having rotatable type-bearing sleeves each with two type-bearing faces, one of which faces is normally opposite the platen, mechanism for partially rotating the sleeves to bring their other faces opposite the platen, devices for locking the type-bars during the operation of said mechanism, means for first throwing the locking devices into operation, then operating the sleeve-rotating mechanism and finally throwing the locking devices out of operation, and keys for operating the type-bars when either of the faces of the sleeves is opposite the platen.

17. The combination of a platen, pivoted type-bars having rotatable type-bearing sleeves, each with three type-bearing faces, each of which has three type longitudinally arranged thereon and one of which faces is normally opposite the platen, mechanism for partially rotating the sleeves in either direc-

tion to bring their other faces opposite the platen, devices for locking the type-bars during the operation of said mechanism, means for first throwing the locking devices into operation, then operating the sleeve-rotating mechanism and finally throwing the locking devices out of operation, and keys three for each type-bar for operating the type-bars when either of the faces of the sleeves is opposite the platen, one of which keys merely swings the type-bar about its pivot, another swings it about its pivot and advances its pivot toward the platen, and the third swings the type-bar about its pivot and moves its pivot away from the platen.

18. The combination of the type-bars having rotating type-bearing sleeves with multiple type-bearing faces, and teeth or projections, an endwise-movable shifting-rack with which said teeth on the sleeve normally engage, the slotted guiding-plates 30, with one slot for each type-bar, the endwise-movable locking-comb having locking hooks or teeth, one for each type-bar and means for throwing the locking-comb into engagement with the type-bars, then operating the rack to partially rotate the sleeves and finally throwing the locking-comb out of engagement with the type-bars.

19. The combination of the type-bars having rotating type-bearing sleeves with multiple type-bearing faces and teeth or projections, a latch for locking each sleeve in any position to which it may be adjusted, an endwise-movable shifting-rack with which said teeth on the sleeve normally engage, the slotted guide-plate 30 with one slot for each type-bar, the endwise-movable locking-comb having locking hooks or teeth, one for each type-bar, and also latch-tripping lugs, one for each latch, and means for throwing the locking-comb into action to lock the type-bars and trip the latches, then operating the rack to partially rotate the sleeves, and finally throwing the locking-comb out of engagement with the type-bars and causing the reengagement of the locking-latches with the type-bearing sleeves.

20. The combination of the type-sleeve-shifting rack, a laterally-movable plate having an inclined slot 39³ therein, lever connections between the plate and rack, and a shift-

ing-key having a lug that travels in said slot when the key is depressed, substantially as set forth.

55

21. The combination of the type-sleeve-shifting rack, a laterally-movable plate having two inclined divergent slots therein, lever connections between the plate and rack, a shifting-key having a lug that travels in one of said slots when the key is depressed, and a second shifting-key having a lug that travels in the other of said slots when its key is depressed, whereby on the depression of one key the rack is moved from a normal position endwise in one direction and on the depression of the other key the rack is moved endwise from the normal position in the reverse direction, substantially as set forth.

60

22. The combination of the endwise-movable type-bar-locking comb, a laterally-movable plate having the irregularly-shaped slot 40² therein, lever connections between the plate and locking-comb, and a key having a lug that travels in said slot when the key is depressed, whereby when the key is depressed the locking-comb is moved endwise, then remains at rest and is finally moved endwise in a reverse direction, substantially as set forth.

70

23. The combination of the type-sleeve-shifting-rack, the locking-comb, the laterally-movable plate having inclined divergent slots 39², 39³, the laterally-movable plate having similar irregularly-shaped slots 40², 40³, a shifting-key having a lug which when the key is depressed travels in the slots 39² and 40², and a second key having a lug which when the key is depressed travels in the slots 39³ and 40³, whereby on the depression of the first-named key the locking-comb is thrown into operation, the shifting-rack then operated in one direction and finally the locking-comb withdrawn to its normal position, and when the second key is depressed the same operation occurs except that the shifting-rack is operated in the reverse direction.
